ELECTRICAL AMPLIFYING DEVICE

Robert H. Worrall, Washington, D. C.

Application December 11, 1935, Serial No. 53,936

15 Claims. (Cl. 250—41.5)

(Granted under the act of March 3, 1883, as amended April 30, 1928; 370 O. G. 757)

My invention relates broadly to electrical amplifying devices and more particularly to methods of and means for varying a direct current potential derived from a circuit including a light-sensitive cell so that effectively alternating potentials may be impressed upon input terminals of an alternating current amplifying device.

One object of my invention is to provide a method and means for amplifying the output of a photo-electric cell circuit or other device that furnishes as an output a direct current of comparatively small magnitude, by using a straight alternating current amplifier.

Another object of my invention is the variation of D. C. potentials so as to make them effectively alternating in character.

Another object of my invention is to provide a method and means for creating a controllable alternating potential in a circuit which includes a photo-electric cell, wherein the cell itself forms no part of the oscillating circuit proper.

Another object of my invention is to provide a means for amplifying the energy controlled by a photo-electric cell directly through the medium of an alternating current audio frequency amplifier, instead of the direct current amplifier customarily used, to furnish a reliable, simple, and inexpensive means for amplifying such energy.

Other objects and advantages of the invention will be apparent from the following description, taken in connection with the accompanying drawings, wherein the figures show several circuit diagrams that illustrate some of the preferred embodiments of my invention.

In Figs. 1 and 2 the magnitude of the impressed D. C. potential from a photo-electric cell circuit is caused to vary by means of a periodically varying capacity.

In Figs. 3, 4, and 5 an alternating E. M. F. from an external source is applied to vary the magnitude of the impressed D. C. potential derived from a light-sensitive cell circuit.

In Figs. 6 and 7 the magnitude of the impressed D. C. potential from a light-sensitive source is varied by means of iron cored coils, connected in the circuit, and influenced by an externally applied fluctuating magnetic field.

A light-sensitive cell which has radiation from a light source impressed upon its sensitive surface sets up a source of direct current E. M. F. This E. M. F., impressed directly upon the grid of a vacuum tube, can only be amplified by a D. C. amplifying circuit. By the methods disclosed in this invention, the said E. M. F. may be varied so as to actuate the input circuit of a

vacuum tube, or other electrical device, in the same manner as though alternating potentials were impressed.

In the figures, like numerals are used to designate like parts throughout.

Referring to Fig. 1, numeral 1 is an external light source capable of radiating luminous energy when lighted; 2 is a light-sensitive cell, either photo-electric or photo-galvanic, having an anode element 3 and a cathode element 4; 5 is a split, 10 rotary, or other type of variable condenser connected across the anode and cathode of the light-sensitive cell; and 6 is an electron tube which may be of the three or more element type. For purposes of illustration, a three element, heater 15 type tube is shown, having a cathode 7, a heater element 8, energized from any conventional power source, a control grid 9 and an anode 10. A grid leak or biasing resistor 11 is connected from control grid 9 to the negative side of a biasing 20 battery 12, whose positive terminal is connected to the cathode 7. From the junction of biasing resistor 11 with the negative terminal of biasing battery 12, one cathode branch connection leads directly to one side of condenser 5, and on to 25 anode 3 of cell 2. From the cathode 4 of said cell a connection proceeds to the opposite side of condenser 5, on through a fixed condenser 13, whose presence in the circuit is optional, to the opposite side of grid biasing resistor 11, and 30 thence to control grid 9. The position of fixed condenser 13 need not be exactly as shown but may be between cathode 4 and condenser 5, or elsewhere as desired to produce like results. Another cathode branch connection leads from 35 cathode 7, to the center tap of heater transformer secondary 14, which is connected across heater element 8, and from said center tap to negative "B" battery terminal 15. The anode 10 is connected to an external load circuit which, 40 for purposes of illustration, is shown here as a condenser 16, connected across the primary of an iron cored transformer 17. From the other side of this load circuit, the anode lead proceeds to the positive "B" battery terminal 18. It will be understood that any suitable form of output circuit may be used in place of the one here shown, but, as illustrated, the secondary of transformer 17 is connected to further stages of amplification.

Referring to Fig. 2, the circuit is identical with that described in Fig. 1, except that variable condenser 30, having characteristics similar to condenser 5 previously described, is substituted 55

in place of fixed condenser 13, which is omitted and variable condenser 5 is eliminated.

Fig. 3 is identical with Fig. 2, except that variable condenser 30 is removed from the circuit, thus placing biasing resistance 11 directly across the anode and cathode of the light-sensitive cell 2, and an alternating E. M. F. from an external source 19 is impressed across all or part of biasing resistance 11 by means of an adjustable contact 20.

Fig. 4 is identical with Fig. 3, except that a cathode resistor 21 is inserted in the circuit between cathode 7 and all other connections to this cathode, and the alternating E. M. F. from external source 19 is applied across all or part of this cathode resistor 21 by means of adjustable contact 22.

Fig. 5 is identical with Fig. 3, except that an additional resistance 23 is inserted in series between the anode 3 of the light-sensitive cell and the biasing resistance 11, and the alternating E. M. F. from external source 19 is applied through optional fixed condensers in each branch, 24 and 25, across all or part of this resistance 23 by means of adjustable contact 26.

Fig. 6 is identical with Fig. 3, except that the externally applied A. C. from source 19 is removed and, between the biasing resistance 11 and the grid 9, iron cored coils 27 and 28 are connected in series with each other and with the circuit. Said coils are spaced in relation to each other and between them is inserted a rotating permanent magnet 29, which may be replaced by a stationary iron core, energized from a separate A. C. source.

Fig. 7 is identical with Fig. 6, except that the iron cored coils 27 and 28 and the rotating or alternating member 29, described under the latter figure, are removed from the grid circuit and similar members 31, 32, and 33 are connected, in the same mutual relation as before, in the plate circuit, between the output or load circuit and the positive "B" battery terminal 18.

Referring to Fig. 1, the method of operation is as follows: When light from the source 1 is caused to strike the light-sensitive cell 2, a difference of potential is set up across the anode 3 and the cathode 4, causing a current to flow in resistor 11, if optional condenser 13 is omitted. If condenser 13 is inserted, a voltage will be impressed across it. This effect will, of course, be greatly magnified if the cell 2 is properly biased by a direct current potential from a suitable source. This E. M. F., through the medium of either arrangement will, in turn, be impressed upon the grid 9 of electron tube 6. Under these conditions, since no continuous variation is taking place in this impressed grid voltage, the output current from tube 6 will assume and maintain a steady value. The aforesaid potential which is impressed upon the entire circuit only when the cell 2 is illuminated, will also be impressed upon condenser 5, which we will assume happens to be set for a maximum capacity. This condenser 65 will then take on a charge in accordance with

$$Q = CE \left(1 - e^{-\frac{t}{RC}} \right)$$

70 or, ignoring the time factor, such a charge Q will be a function of the capacity C of condenser 5 and the potential E which is impressed as a result of illuminating the cell 2. Since the cell 2 has high inherent resistance, the potential of the cell 75 at the instant of illumination before current be-

gins to flow in the external circuit will be a maximum. At this instant the voltage impressed across the condenser 5 will also be a maximum. Now, as 5 begins to assume a charge, and current begins to flow in the external circuit of the cell, 5 the current flowing through the cell will vary in accordance with its own IR drop and the back E. M. F. developed by condenser 5 and the rest of the circuit. Condenser 5 will continue to charge until the voltage across it equals the voltage impressed as a result of illuminating the cell 2. Therefore, during this transitory interval, the potential developed across 5 varies from zero to that of the impressed voltage.

If, prior to illuminating the cell, the condenser 15 5 is steadily rotated so as to vary continuously its capacity, the potential of the grid 9 will not be affected, but if the cell be illuminated while the capacity of 5 is thus continuously varying, the potential across and the charge upon 5 will be 20 varied, and this variation will be transmitted to and impressed upon the grid 9 of the tube 6. This voltage impressed upon the grid will vary in synchronization with the capacity variation of condenser 5. The voltage variation thus impressed upon 25 the grid will cause a synchronous variation of the current flowing in the output or plate circuit of tube 6. If this plate current variation is at audio frequency, it may be amplified to any desired extent through conventional transformer 30 type audio frequency amplifiers, one of which is indicated in the figure for purposes of illustration. No limitation, however, is implied as to the frequency range over which the grid voltage may be varied to produce the results described above. 35

In Fig. 2, the functions of the circuit are essentially the same as described in connection with Fig. 1. The only change here is that the condenser 30, which is similar to 5 and performs similarly in the circuit, is connected between the 40 grid 9 and the light-sensitive cell 2, instead of across the cell.

In Fig. 3, an alternating E. M. F. from an external source 19 is impressed upon the grid 9 in such a manner that, with the cell 5 darkened, 45 the grid potential resulting from the combination of biasing potential 12 and the alternating E. M. F. from source 19 will swing from such a neutral or negative value to such a further negative value that no current, or relatively little current, will flow in the output circuit of tube 6. When the cell 2 is illuminated, however, an additional D. C. potential of a steady value is impressed upon the grid 9. The alternating E. M. F. from 19 will, during one-half cycle, augment, and 50 during the next half cycle, oppose this D. C. potential, with the result that during some part of each complete cycle of the source 19, the potential of grid 9 will swing sufficiently in a positive direction to permit a relatively large plate current to flow in the output circuit of tube 6. Thus the cell operated D. C. voltage will control the average value of the total potential impressed upon the grid 9, and the grid potential will be varied at the frequency of the external source 55 of alternating potential 19. The over-all result will be a pulsating component of plate current in the output circuit of tube 6. This pulsating current will flow only when cell 2 is illuminated, and it will attain successive maxima at the frequency of the source 19. Such a current is easily amplified by any well known alternating current amplifying means.

The principle of operation of the circuit shown in Fig. 4 is the same as described for Fig. 3. The 75

only difference between these two embodiments of the basic invention is that, in Fig. 4 the alternating potential from external source 19 is applied across an additional resistor connected directly in the cathode circuit of the tube 6, and this may require the use of a higher initial grid bias from biasing potential 12 in order to accomplish the same results as described for Fig. 3.

The circuit of Fig. 5 illustrates another modification of the basic principle employed in Figs. 3 and 4. Here the alternating potential from external source 19 is impressed across an additional resistor between one of the electrodes of cell 2 and biasing resistance 11, and optional fixed condensers 24 and 25 may be inserted in the leads from said source, otherwise the circuit is identical with Fig. 3. When the circuit is employed in the manner described for Fig. 3, the grid of the tube is biased so that no current, or relatively little current, will flow in the plate circuit thereof when biasing potential 12 and external source 19 alone are acting. When the tube is illuminated, an additional D. C. potential is impressed upon the grid of the tube and this is successively opposed and augmented by the alternating potential from 19, so that during some part of each cycle of 19, the combined potentials acting on the grid will cause it to swing sufficiently in a positive direction to permit a relatively large pulse of current 20 to flow in the output circuit of the tube. The characteristics of this current are the same as described for Fig. 3.

The circuit shown in Fig. 5 possesses the additional characteristic of being able to function as a relaxation circuit. In this incarnation, the relaxation circuit proper comprises the source of biasing potential 12, biasing resistance 11, and the total impedance, as measured from grid to cathode, of the vacuum tube 6 and its associated output circuit. The characteristics of this relaxation circuit are controlled by the values assigned to resistance 11, battery 12, or both. When the cell 2 is dark and no alternating potential is being supplied from 19, relaxation oscillations will occur in the circuit 12, 11, and 6. Should the cell 2 now be illuminated, the additional D. C. potential impressed thereby will upset the conditions of bias in the grid circuit of the tube which served to maintain the relaxation oscillations, and these oscillations will cease. Thus, darkening and illuminating the cell 2 will control the starting and stopping of relaxation oscillations in the relaxation circuit described. The effect of these relaxation oscillations in the grid circuit of the tube will be to cause an otherwise direct plate current of a steady value to pulsate. Such a pulsating current may then be amplified by the usual type of transformer coupled amplifier, as shown.

60 The relaxation oscillations described may be caused to start instead of stop when the cell 2 is illuminated, by merely changing the bias on the photocell, or on the tube, or on both, which methods are well known to the art.

65 The embodiment of the invention illustrated by the circuit of Fig. 6 operates as follows: When the cell 2 is dark and the iron cored coils 27 and 28 are being acted upon by a fluctuating magnetic field set up about the armature 29, the grid 9 of the vacuum tube is so biased by means of 12 that no current, or relatively little current, will flow in the plate circuit of the tube. If the cell 2 is now illuminated, an additional D. C. potential will be impressed on the grid 9. This will cause a 70 current to flow through the coils 27 and 28, in-

ducing a magnetic field which will interact with the magnetic field set up by armature 29. The result of this interaction will be to cause the potential of grid 9 to swing sufficiently in a positive direction during some part of the cycle of the fluctuating magnetic field about 29, to permit a relatively large component of plate current to flow in the output circuit of the vacuum tube. This current will be pulsating in character and will pass through successive maxima at the frequency of the fluctuating magnetic field. Such a current may easily be amplified to any desired extent by conventional alternating current amplifying means, such as the transformer coupled amplifier indicated in the figure.

In the circuit of Fig. 7, the function of the various elements is the same as described for Fig. 6, the only difference in the two circuits being in the location of the armature and the iron cored coils. In this circuit, coils 31 and 32, and 20 armature 33, which have similar characteristics in all respects to elements 27, 28, and 29, described in connection with Fig. 6, are included directly in the plate circuit of the vacuum tube, between the connection to the transformer primary and the positive B battery terminal. In operation, the grid of the tube is biased so that no plate current, or relatively little plate current, will flow when the tube is dark. When the tube is illuminated, an additional D. C. potential is 30 applied to the grid of the tube, sufficient to cause a continuous, relatively large plate current to flow in the output circuit of said tube. This current will flow through the coils 31 and 32, setting up a magnetic field which will interact 35 with the magnetic field set up about armature 33. The result of this interaction will be a pulsating current in the plate circuit of the vacuum tube, which will pass through successive maxima at the frequency of the fluctuating magnetic 40 field set up about armature 33, and which may be amplified to any desired extent by ordinary alternating current amplifying means.

The invention described herein may be manufactured and used by or for the Government of 45 the United States of America for governmental purposes without the payment of any royalties thereon or therefor.

I claim:

1. In an electrical circuit which includes a 50 light-sensitive source of direct current potential, said source producing an uninterrupted direct current due to the incidence of substantially constant illumination upon the light-sensitive portion thereof, the method of imparting alternating characteristics to the output of said source which comprises cyclically varying the capacitive reactance of said circuit.

2. In an electrical circuit which includes a 55 light-sensitive source of direct current potential, said source producing an uninterrupted direct current due to the incidence of substantially constant illumination upon the light-sensitive portion thereof, the method of amplifying the output of said source which comprises, imparting alternating characteristics thereto by cyclically varying the capacitive reactance of said circuit, and amplifying the resultant energy by alternating current amplifying means.

3. In an electrical circuit which includes a 70 light-sensitive source of direct current potential, said source producing an uninterrupted direct current due to the incidence of substantially constant illumination upon the light-sensitive portion thereof, the method of amplifying the output 75

of said source which comprises, imparting alternating characteristics thereto by cyclically varying the capacitive reactance of said circuit, applying the resultant energy to the grid of a thermionic tube to cause a component of current to flow in the plate circuit of said tube during part of each cycle of said reactance variation as a result of the application of said energy to said grid, and amplifying by alternating current means the pulsating current thus produced in said plate circuit.

4. In an electrical circuit which includes a light-sensitive source of direct current potential, said source producing an uninterrupted direct current due to the incidence of substantially constant illumination upon the light-sensitive portion thereof, the method of amplifying the output of said source which comprises, applying said output to the grid of a thermionic tube to control the potential of said grid in accordance with said output and an alternating potential of a steady average value applied to said grid from a source external to said circuit, causing a component of current to flow in the plate circuit of said tube during part of each cycle of said alternating potential as a result of the application of said output to said grid, and amplifying by alternating current means the pulsating current thus produced in said plate circuit.

5. In an electrical circuit which includes a light-sensitive source of direct current potential, said source producing an uninterrupted direct current due to the incidence of substantially constant illumination upon the light-sensitive portion thereof, the method of imparting alternating characteristics to the output of said source which comprises, cyclically varying the inductive reactance of said circuit by electromagnetic interaction between a magnetic field set up by said output within said circuit and a fluctuating magnetic field set up outside said circuit.

6. In an electrical circuit which includes a light-sensitive source of direct current potential, said source producing an uninterrupted direct current due to the incidence of substantially constant illumination upon the light-sensitive portion thereof, the method of amplifying the output of said source which comprises, imparting alternating characteristics thereto by cyclically varying the inductive reactance of said circuit by electromagnetic interaction between a magnetic field set up by said output within said circuit and a fluctuating magnetic field set up outside said circuit, and amplifying the resultant energy by alternating current amplifying means.

7. In an electrical circuit which includes a light-sensitive source of direct current potential, said source producing an uninterrupted direct current due to the incidence of substantially constant illumination upon the light-sensitive portion thereof, the method of amplifying the output of said source which comprises, imparting alternating characteristics thereto by cyclically varying the inductive reactance of said circuit by electromagnetic interaction between a magnetic field set up by said output within said circuit and a fluctuating magnetic field set up outside said circuit, applying the resultant energy to the grid of a thermionic tube to cause a component of current to flow in the plate circuit of said tube during part of each cycle of said fluctuating magnetic field as a result of the application of said energy to said grid, and amplifying by alternating current means the pulsating current thus produced in said plate circuit.

8. In an electrical circuit which includes a light-sensitive source of direct current potential, said source producing an uninterrupted direct current due to the incidence of substantially constant illumination upon the light-sensitive portion thereof, in combination, a continuously varying capacity in circuit with said source, a thermionic tube with appropriate power supply, grid leak, and biasing potential, so connected that the output of said source, after being operated upon by said capacity, will be impressed upon the grid of said tube to cause variations in the potential of said grid, and an alternating current amplifying device in the output circuit of said tube, whereby alternating characteristics are imparted to the direct current output from said source and said output may be amplified by said alternating current amplifying device.

9. In an electrical circuit which includes a light-sensitive source of uninterrupted direct current potential, said source producing said potential only when the light-sensitive portion thereof is continuously illuminated, in combination, a thermionic tube with appropriate power supply, grid leak, and biasing potential, an alternating potential from an external source applied directly across a resistance in the input circuit of said tube so as to vary the potential of the grid thereof, said grid being so biased that no current, or relatively little current, will flow in the plate circuit of said tube while said alternating potential alone is acting upon said grid, means for applying the output of said source to raise the potential of said grid to the point where a component of current will flow in the plate circuit of said tube during part of each cycle of said alternating potential as a result of the application of said output to said grid, and an alternating current amplifying device in the output circuit of said tube, whereby the direct current from said source may be amplified by said alternating current amplifying device.

10. In an electrical circuit which includes a light-sensitive source of uninterrupted direct current potential, said source producing said potential only when the light-sensitive portion thereof is continuously illuminated, in combination, a thermionic tube with appropriate power supply, grid leak, and biasing potential, means within said circuit for setting up a magnetic field with power from said source, means for applying a fluctuating magnetic field from an external source to interact with first said magnetic field, means for impressing the energy from said source after being operated upon by said fluctuating magnetic field upon the grid of said tube to cause variations in the potential of said grid with corresponding variations in the current flow in the output circuit of said tube, and an alternating current amplifying device in said output circuit, whereby the direct current output from said source may be amplified by said alternating current amplifying device.

11. In an electrical circuit which includes a light-sensitive source of uninterrupted direct current potential, said source producing said potential only when the light-sensitive portion thereof is continuously illuminated, in combination, a thermionic tube with appropriate power supply, grid leak, and biasing potential, means within said circuit for setting up a magnetic field with power controlled by a current flow from said source, means for applying a fluctuating magnetic field from an external source to interact with first said magnetic field to impart alter-

nating characteristics to the energy flowing within said circuit, and an alternating current amplifying device in the output circuit of said tube, whereby the direct current output from said source may be amplified by said alternating current amplifying device.

12. In a circuit energized from a light-controlled direct current source of relatively low potential, having an anode and a cathode branch, 10 in combination, an electron tube having anode, cathode, and grid elements with conventional power supply, a source of grid biasing potential, a grid leak, an output circuit which includes the plate of said tube, and a continuously varying 15 capacity in the input circuit of said electron tube for the purpose of cyclically varying the potential impressed upon the grid thereof, whereby the output of said tube is given a character suitable for further amplification by alternating 20 current means.

13. In a circuit energized from a light-controlled direct current source of relatively low potential, having an anode and a cathode branch, 25 in combination, an electron tube having anode, cathode, and grid elements with conventional power supply, a source of grid biasing potential, a grid leak, an output circuit which includes the plate of said tube, and an electro-magnetic assembly, consisting of inductive elements within 30 the field of a magnetic element of fluctuating polarity, in circuit with the enumerated combination for cyclically varying the output of said tube so as to give it a character suitable for further amplification by alternating 35 current means.

14. In a light-sensitive relaxation oscillator circuit, a thermionic tube having anode, cathode, and grid elements with appropriate power supply, a source of biasing potential, resistance elements and capacity in the input circuit of said 40 tube, said capacity being supplied in whole or in part by the inter-electrode capacities of said tube, an output circuit connected to the anode of

said tube, the circuit constants of the aforesaid combination being so assigned that a change in the bias on said grid may cause relaxation oscillations to commence and continue to flow in the input circuit of said tube, or, once flowing, 5 to stop, depending upon the initial grid bias, and a light-sensitive source connected to impress a controlling direct current potential upon the grid of said tube when the light-sensitive element thereof is illuminated, whereby current variations 10 in said output circuit will occur while relaxation oscillations are flowing in the input circuit of said tube, and said variations may be caused to start or stop by illuminating or darkening the light-sensitive element of said source. 15

15. In a light-sensitive relaxation oscillator circuit, a thermionic tube having anode, cathode, and grid elements with appropriate power supply, a source of biasing potential, resistance elements and capacity in the input circuit of said 20 tube, said capacity being supplied in whole or in part by the inter-electrode capacities of said tube, an output circuit connected to the anode of said tube, the circuit constants of the aforesaid combination being so assigned that a change 25 in the bias on said grid may cause relaxation oscillations to commence and continue to flow in the input circuit of said tube, or once flowing, to stop, depending upon the initial grid bias, a light-sensitive source connected to impress a 30 controlling direct current potential upon the grid of said tube when the light-sensitive element thereof is illuminated, and alternating current amplifying means in said output circuit, whereby current variations in said output circuit will occur 35 while relaxation oscillations are flowing in the input circuit of said tube, and said variations may be amplified by said amplifying means, or may be caused to start or stop by illuminating or darkening the light-sensitive element of said 40 source.

ROBERT H. WORRALL.
